[57] CLAIM

The ornamental design for a fluorescent lamp with
simulative gaslight cover, as shown and described.

DESCRIPTION

FIG. 1 is a front elevational view of a fluorescent lamp
with simulative gaslight cover showing my new design,
the rear being a mirror image;

FIG. 2 is a side elevational view thereof, the opposite
side being a mirror image;

FIG. 3 is a top plan view thereof; and

FIG. 4 is a bottom plan view thereof.

FIG. 1

FIG. 2

FIG. 3

FIG. 4
